Atty.

UNITED STATES PATENT OFFICE.

JOHN W. F. MACDONALD, OF BRIGHTON, MASSACHUSETTS, ASSIGNOR TO THE MERRILL PROCESS COMPANY, A CORPORATION OF MASSACHUSETTS.

HEATING APPARATUS.

1,278,068.

Specification of Letters Patent.

Patented Sept. 3, 1918.

Application filed February 8, 1918. Serial No. 216,142.

To all whom it may concern:

Be it known that I, JOHN W. F. MACDONALD, a citizen of the United States, and a resident of Brighton, county of Suffolk, and 5 State of Massachusetts, have invented Improvements in Heating Apparatus, of which the following is a specification, reference being had to the accompanying drawings, forming part thereof.

10 This invention has reference to improvements in heating apparatus utilizing a circulating heat transporting medium.

The main object of the present invention is to control the supply of heat to the 15 circulating heat carrying medium through a predetermined variation of the condition of said medium.

Another object of the invention is to so 20 construct a heating apparatus comprising a conduit through which a heat transporting medium may be mechanically circulated between a point of heat absorption and a point of heat utilization that variation of fluidity or flow of said medium may act to control 25 the supply of heat to said conduit at the point of heat absorption.

Other objects of the invention will appear from the following description.

The invention consists in the conduit having 30 a point of heat absorption to which point heat is supplied and a controller adapted to be actuated by a variation in the condition of a heat carrying medium circulating in said conduit to control the source 35 of said heat.

The invention also consists in such other novel features of construction and combination of parts as shall hereinafter be more fully described and pointed out in the 40 claims.

Figure 1, represents a front view of the improved heating apparatus showing the controller for controlling the supply of liquid fuel to the furnace.

45 Fig. 2, represents an enlarged sectional view taken on line 2—2 Fig. 3.

Fig. 3, represents an end view of the controller with a portion of a connecting pipe shown in section as taken on line 3—3

50 Fig. 1.

Similar characters of reference designate corresponding parts throughout.

In heating apparatus of this nature a viscous heat carrying medium is usually em-

ployed for transporting heat from a heat 55 absorbing point to a point at which said heat is to be utilized. Such heat carrying medium is mechanically circulated through the continuous conduit constituted by the delivery pipe 5 and the return pipe 6 connected at their respective ends by the pipes 7 and 8 of which pipe 7 extends through the furnace 9 and has the coil or other suitable conduit 10 through which the heat carrying medium is circulated during its sub- 60 junction to heat generated by the combustion of fluid fuel supplied to the burner 11 of said furnace 9 through the fuel supply pipe 12. Pipe 8 has the heat radiating coil 13 or other means to utilize heat transported to 70 such coil 13 or means by the viscous heat carrying medium in the circulation of said medium from the furnace 9 through pipe 5, which circulation is controlled by valve 14 of said pipe 5. Pipe 6 has the expansion 75 pipe 15 and the valve 16 located at the suction side of and close to the pump 17 the pump chamber of which communicates with the return pipe 6.

By means of the pump 17 the viscous heat 80 carrying medium is caused to circulate in the continuous conduit constituted by the pipes 5 and 6 and their connections 7 and 8 and their coils or members 10 and 13. It is to be noted that the pressure of the pump 85 is exerted directly on the viscous material in the pipe 6 between said pump 17 and the pipe 7 on coil 10 and that the pressure on this portion of said viscous material is somewhat greater than on said material passing 90 from the coil 10 and pipe 5 to the point or coil 13 of utilization. In this latter portion of the continuous conduit the viscous material is of a higher temperature and consequently somewhat more fluid than adja- 95 cent the pump.

Connected respectively with the pipes 5 and 6 are the pipes 18 and 19 of which the pipe 18 receives the viscous fluid of the higher temperature and less viscosity from 100 pipe 5 while the pipe 19 receives said viscous material of comparatively lower temperature and greater viscosity from pipe 6. Mounted between the ends of said pipes 18 and 19 is the frame 20 having the chambers 105 21 and 22 with which said pipes 18 and 19 respectively communicate. Said chambers 21 and 22 respectively have the walls 23 and

24 having perforations through which extends the rod 25 having the heads 26 and 27 which bear against the diaphragms 28 29 of the metallic bellows 30 and 31 located in 5 said chambers 21 and 22. On said rod 25 are adjustable the actuator nuts 32 and the stop member 33 between which latter and the wall 23 is located the expansion spring 34.

10 From the wall 24 extends the member 35 carrying the pivoted lever 36 which at its upper end 37 engages rod 25 and bears against one of the actuator nuts 32 and at its lower end has the latch 38 to engage pin 15 39 of lever 40. This lever 40 is pivotally sustained in the frame 41 extending below said walls 23 and 24 and having the member 42 between which and said lever 40 is the tension spring 43 which tends constantly 20 to move said lever in a direction to operate the valve rod 44, pivotally connected with said lever 40, to close its valve which latter is of any usual construction and is contained in the ordinary valve housing 45 of the 25 fluid fuel supply pipe 12.

In the operation of this controller pressure of viscous material in pipe 19 acting on the diaphragm 29 of bellows 31 in chamber 22 will, to some extent, balance the pressure of the viscous material in pipe 18 acting on the diaphragm 28 of bellows 30 in chamber 21 and the difference between such pressures will be compensated for by spring 34 under suitable adjustment of the stop 35 member 33. If now the pressure in pipe 5 and, consequently, in pipe 18 increases from undue expansion of the viscous material in said pipe 5 by reason of an unduly high temperature or because of the closing of valve 40 14 while pump 17 continues to operate, such pressure acting on diaphragm 28 will move said diaphragm 28 and rod 25, against the pressure on diaphragm 29, with the result that the nut 32 will act on end 37 of lever 45 36 to swing said lever 36 sufficiently to disengage its latch 38 from pin 39 of lever 40 whereupon said lever 40 will be drawn downward by spring 43 and will operate valve stem 44 to close the valve of housing 50 45 thus shutting off the supply of fuel passing through pipe 12 to the furnace burner 11.

In some cases it may be desirable to operate the controller through or as a result of 55 an undue increase of temperature in the viscous material in pipe 5 acting directly on similar or dissimilar material in pipe 18 in which case it may and usually would be preferred to dispense with the compensating 60 pressure exerted on diaphragm 29 and said diaphragm and its chamber could then be eliminated, care being taken to adjust the action of spring 34 accordingly or this spring could, in such case, be removed.

65 It is evident that the release of the spring

actuated lever 40 will permit the movement of said lever and its rod 44 in a direction which results in the closing of the valve controlling the flow of fuel through pipe 12 to burner 11 so that undue supply of 70 fuel to said burner 11 is prevented under abnormal condition of the heat carrying material or liquid in the conduit 5.

Having thus described my invention I claim as new and desire to secure by Letters 75 Patent:

1. Heating apparatus of the nature described comprising a continuous conduit having a point of heat absorption and a point of heat radiation, a pump to operate 80 on liquid in the return member of said conduit, viscous substantially non-expansible liquid filling said conduit, whereby the heat acquired by said liquid at said point of heat absorption is reduced during the circulation 85 of said liquid and the viscosity of the liquid thereby increased, a burner adjacent said point of heat absorption and having a fuel supply pipe provided with a controlling valve, a balanced controller for said fuel 90 valve, and pipes connecting said controller with the respective members of said conduit at points close to and at opposite sides of said point of heat absorption, one of said pipes connected with said conduit between 95 said pump and said point of heat absorption.

2. Heating apparatus of the nature described comprising a continuous conduit having a point of heat absorption, a burner 100 adjacent said point of heat absorption having a fluid fuel supply having a controlling valve, viscous material filling said conduit, a pump connected with a member of said conduit at one side of said heating point, 105 pipes leading from the respective members of said conduit at opposite sides of said point of heat absorption, and a controller for said fuel supply valve having a pair of actuating means connected to be operated by 110 material in said pipes and a compensating means normally to compensate for a difference of pressure in said pipes.

3. Heating apparatus of the nature described comprising a continuous conduit 115 having a point of heat absorption and a point of heat utilization, a burner adjacent said point of heat absorption having a fluid fuel supply pipe provided with a controlling valve, viscous material filling said conduit, 120 means to circulate said viscous material toward said point of heat absorption, whereby the condition of said viscous material in the respective members of said conduit may vary as to pressure, temperature and fluidity, and means connected with said conduit for controlling the actuation of said fuel supply valve, said controlling means having an element to be influenced by a variation of the pressure of viscous material in 125 130

one member of said conduit balanced by an element under pressure of viscous material in the other member of said conduit.

4. Heating apparatus of the nature described comprising a continuous conduit having a point of heat absorption, a burner adjacent said point of heat absorption having a fluid fuel supply having a controlling valve, viscous material filling said conduit, 5 a pump connected with a member of said conduit at one side of said heating point, pipes leading from the respective members of said conduit at opposite sides of said point of heat absorption, a controller hav-

ing a pair of chambers with which said 15 pipes respectively connect, diaphragms yieldingly mounted in said chambers, a shift rod against which said diaphragms act, a compensating spring acting to move said rod in one direction, a spring actuated 20 means for closing said fuel supply valve, and a device for holding said spring actuated means against closing movement, said device adapted to be acted upon by a member of said shift rod to release said spring 25 actuated means.

JOHN W. F. MACDONALD.
